KNOCKDOWN CRANE BOOM

Robert Gilmore Le Tourneau, Peoria, Ill., assignor
to R. G. Le Tourneau, Inc., a corporation of
California

Application June 5, 1940, Serial No. 338,941
In Brazil May 8, 1940

4 Claims. (Cl. 212—8)

This invention relates to portable wheel mounted cranes adapted to be connected to and operated from a tractor, and particularly represents improvements over the crane shown in my U. S. Letters Patent No. 2,078,393.

The crane includes a relatively long and odd shaped boom, which in the crane as originally built was constructed as a permanent welded unit incapable of being dismantled. As a result, difficulties in shipment from the factory or other points of distribution were frequently encountered.

It is therefore the principal object of the present invention to avoid these difficulties by constructing the boom of a number of separate parts with means to easily and quickly connect these parts together in a detachable manner, and so that the boom when completely assembled, will have adequate strength and rigidity, coupled with the desired lightness in weight.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of my improved crane as attached to a tractor.

Figure 2 is a rear end view of the crane with the cables removed.

Figure 3 is a fragmentary longitudinal section showing the connection of the boom with the wheeled supporting truck.

Figure 4 is a fragmentary side view of a pair of boom legs at their lower end, separated from each other.

Figure 5 is a cross section on line 5—5 of Fig. 4.

Figure 6 is a sectional plan on line 6—6 of Fig. 2.

Figure 7 is a similar view on line 7—7 of Fig. 2.

Figure 8 is a cross section on line 8—8 of Fig. 1.

Referring now more particularly to the characters of reference on the drawings, the crane comprises a long tongue 1, upwardly trussed near its rear end so as to avoid possible sagging, and adapted at its forward end for swivel supporting connection with a tractor 2. The tongue at its rear end is rigid with a cross beam 3 at the ends of which are bosses 4 in which are mounted the outwardly projecting spindles 5 of the sup-

porting wheels 6. The above parts form the supporting base or vehicle of the crane.

The boom of the crane comprises a pair of transversely spaced main rear legs 7 of tubular form provided at their lower end with depending orificed plates 8 turnably supported on the spindles 5 between the bosses and wheels. Secondary tubular and relatively light boom legs 9 project upwardly from legs 7 in forwardly diverging relation thereto from their lower end. At said end, the legs 7 have flat plates 10 secured on their adjacent faces, adapted to engage rigid straps 11 depending from the legs 9 on their opposed faces. The plates and straps are provided with matching holes 12 to receive securing cap screws 13, nuts 14 to receive the threads of the screws being welded on the back side of the plates 10 as shown in Fig. 5. A cross bar B extends between the legs at the bottom and is held in place by the lowest cap screws.

The boom legs, which converge toward their upper end in a transverse plane as shown in Fig. 2, are braced intermediate their ends by a horizontal frame 15 which projects between the front and rear legs and is removably secured in place by U bolts 16 as shown in Fig. 6. At their upper end, the rear legs 7 are connected by a plate 17 removably bolted against plates 18 secured on the legs 7 on their forward face as shown in Fig. 6.

The head of the crane is a unit separate from the boom legs and comprises front and rear sheave blocks 19 and 20 connected by rigid framing 21. The framing at the bottom and intermediate the front and rear sheave blocks is provided with a rigid crossbar 22 resting flatly at its ends on the solid top of the legs 7 and removably secured thereto by bolts 23.

The forward legs at their upper end are provided with upwardly extending straps 24 on their adjacent faces, which abut against and are removably secured by bolts 25 to corresponding straps 26 depending from the sheave block 19 on its opposite sides, as shown in Fig. 8.

The head is thus rigidly but removably tied to the boom legs to form the complete boom unit, in which the rear sheave block 20 is disposed well to the rear of legs 7.

A cable 28 extends from one drum of a two-drum power unit of conventional type on the tractor over and between certain pulleys of the blocks 19 and 20 and over those of the hook or lifting block 30 which is disposed below and in vertical alignment with block 20. The winding of

this cable on its drum raises the block 30 and any load supported thereby and vice versa.

Another cable 31 extends from the other drum of the power unit and then over another pulley of block 19, and then back and forth between said block and an anchor sheave block 32 swivelly mounted on the tongue near its front end. This cable controls the boom and is so arranged that when the cable is wound on the corresponding drum, the boom itself will be raised about the 10 wheel spindles as an axis.

The boom can be swung upwardly from a rearward position at an acute angle to the ground, to a position in which the rear legs 7 are vertical. To prevent the boom from tipping forwardly from such position, plates 33 are provided, which depend from the legs 7 at the front and then rest on the cross beam 3.

From the foregoing description it will be readily seen that I have produced such a device 20 as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by 30 Letters Patent is:

1. In a crane, a boom comprising a head, a pair of rear legs and a pair of front legs, and means detachably securing the legs and head together as a rigid unit, the front and rear legs diverging 35 from their lower end, means detachably connecting the front and rear legs together at their lower

end; the rear legs being relatively heavy and plates secured on and depending from said rear legs to form the axial mounting for the boom.

2. In a crane, a boom comprising a head, a pair of rear legs, a pair of front legs, means detachably connecting the head and legs together as a rigid unit, the front and rear legs diverging from their lower end, elements depending from the rear legs to form the axial mounting for the boom and means detachably connecting the front and rear legs together at their lower end; said connecting means comprising plates on one side of the rear legs having a row of tapped orifices, correspondingly orificed straps depending from the front legs to abut against the plates, and cap screws insertable through the orifices.

3. In a crane, a boom comprising a head, a pair of rear legs and a pair of front legs, and means detachably securing the legs and head together as a rigid unit, the front and rear legs diverging upwardly from each other, and the crane head including a framing having a cross bar resting on and detachably secured on the top of the rear legs, and detachable connections between the front legs at the top and the head at its forward end.

4. In a crane, a boom including front and rear pairs of relatively long legs detachably connected together at their ends, the front legs diverging relative to the rear legs from their lower end and all the legs being spaced apart intermediate their ends, a unitary brace frame fitting between the front and rear legs intermediate their ends and means to detachably clamp the legs and frame together to hold the legs against deviation at the frame.

ROBERT GILMORE LE TOURNEAU.
